(57) **CLAIM**

The ornamental design for an adhesive tape dispenser, as shown and described.

DESCRIPTION

1. Adhesive tape dispenser

1.1 : Top

1.2 : Bottom

1.3 : Left

1.4 : Right

1.5 : Front

1.6 : Back

The subject consists of a flat rectangular body incorporating an elongated slot, with a triangular extension to a single trim point; side members extend laterally at an angle from each side of the body beyond a vee-shaped serration situated on the underside along the forming line; each side member also extends horizontally beyond a vee-shaped serration situated on the underside along the forming line; the left-hand member terminates with a female feature; the right-hand member terminates in a corresponding male feature.
